HAIR CLIPPER

Wellington Arthur Sneed, Blue Grass, Iowa

Application December 30, 1949, Serial No. 136,073

7 Claims. (Cl. 30—232)

1

The present invention relates to hair cutting devices and particularly to hair clippers and the like.

The object and general nature of this invention is the provision of a hair cutting implement by which one may cut his own hair easily and conveniently, especially the hair at the back of the head and neck. More specifically, it is an important feature of this invention to provide a hair cutting device which is especially constructed to be held by one hand, with the fingers engaging the device at its upper portion when it is held back of the neck or head and with the thumb engaging and operating the cutting unit by an upward movement of the thumb, as by the simple act of contracting the hand when it holds the device back of the head, with the finger-receiving portions disposed upwardly.

Further objects of this invention are the provision of a hair cutting device having detachable and interchangeable comb units, so as to adapt the device for most convenient use with either thin or thick hair and for cutting hair of different lengths and/or under variable conditions of use; the provision of a hair cutting device comprising a fixed cutterbar and a swingable cutter blade pivotally associated therewith by means which facilitates adjustment of the pivot axis of the swingable element; and such further objects, advantages, and capabilities as will hereinafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 is a side view of one form of my invention;

Fig. 2 is a bottom view taken along the plane indicated by the line 2—2, Fig. 1;

Fig. 3 is a top view taken along the plane indicated by the line 3—3, Fig. 1;

Fig. 4 is an end view taken substantially along the plane indicated by the line 4—4, Fig. 1, with the swingable cutter blade in a position to begin its cutting stroke;

Fig. 5 is a similar view, showing the swingable cutter blade after starting its cutting stroke;

Fig. 6 is a sectional view taken along the plane indicated by the line 6—6, Fig. 4;

2

Fig. 7 is a detail view of one of the auxiliary comb guide units attachable to the frame of the device;

Fig. 8 is a side view of the comb guide member shown in Fig. 7;

Fig. 9 is an end view of the same comb guide member;

Figs. 10 to 12 are views similar to Figs. 7 to 9, showing another form of auxiliary comb guide;

10 Figs. 13 to 15 are detail views of the swingably mounted cutter blade; and

Fig. 16 is a sectional view showing the latching means for holding the auxiliary comb member in place.

15 Reference will now be made in greater detail to the annexed drawings for a more complete description of this invention. In Figs. 1 to 5, the hair cutting device of the present invention incorporates a frame 1 comprising an elongated

20 member having at one end a finger hold section 2 provided with three finger holes 3 and at the other end with a forked section 4 having sides 5 and 6, the plane of the latter lying at right angles to the plane of the finger hold section 2. Fixed

25 to the forked section 4 of the frame 1, between the sides 5 and 6 thereof, is a U-shaped part 9 which has sides 11 and 12 fixed to the sides 5 and 6. The central section 13 of the U-shaped part 9 carries a stationary cutterbar 14 which is

30 secured in place by bolts 15, or other suitable means, and a toothed comb guide section 16 having a plurality of teeth 17 extending at an acute angle relative to the frame 1 and directed, in general, toward the finger hold section 2. The

35 base or central portion 18 of the comb guide part has grooves 19 aligned with the spaces between the teeth 17, as best shown in Fig. 2.

The sides 11 and 12 are slotted to receive a pivot shaft 23 upon which a rockable cutter unit 24 is swingably mounted. The unit 24 comprises a U-shaped part 25 having sides 26 and 27 apertured to receive the pivot shaft 23. One of the

40 shafts 23 is carried in a shiftable bearing 28, the position of which relative to the frame 1 is adjusted by a screw-threaded member 29 carried in

45 lugs 30 on the side 12, as best shown in Figs. 3 and 5. The other end of the pivot shaft 23 is pressed toward the cutter-bar 14 by a spring biased plunger 33 connected to the shaft 23 and

50 acted upon by a spring 34 disposed in a casing 35 which is fixed to the side 11. Adjustment of the spring 34 is effected by a screw-threaded member 36 at the outer end of the spring casing 35.

The rockable cutter unit 24 has at its central portion an extension 38 which is approximately a

segment of a cylinder and upon which a cutter blade 39, in an angled position, is fixed, as by screws 41 and a clamp bar 42 which the screws 41 fasten to the extension 38. A thumb-receiving socket 43 is formed on the member 24 by a thumb strap 44, attached in any suitable manner to the central section of the U-shaped member 25. The swingable member 24 is biased for movement to the position shown in Figs. 1 and 6 by a torsion spring 47 encircling the shaft 23 and having one end 48 fixed to the stationary frame side 11, and the other end 49 is fixed to the side 21 of the rockable cutter unit 24. A sleeve 51 extends around the spring 47.

The comb guide teeth 17 are primarily designed for use with short hair, as at the back of the neck. For use where the hair is thicker, I provide a pair of auxiliary comb guide units 60 and 70. Referring first to the unit 60, shown in Figs. 10 to 12, the unit comprises a base member 61 having a plurality of grooves 62 and a plurality of openings 63 in which the teeth 64 are fixed. A curved pin 65 is secured to each end of the bar 61 and they are adapted to be detachably received in a pair of openings 66 in the end portions of the U-shaped frame part 9, and held therein by any suitable holding means 67, comprising a lever pivoted at 68, actuated into holding position by a spring 69 and provided with a holding nose 67a engaging the notches in the pins 65 or 73. The pins 65 may be ridged or serrated, if desired. The unit 60 is shaped so that the teeth 64 lie below the teeth 17.

The auxiliary comb guide unit 70 is substantially like the unit 60 except that the teeth 71 are longer than the teeth 64. The base 72 is dimensionally similar to the base 61 and the attaching pins 73 are adapted to be mounted in the openings 66, the same as the pins 65.

The operation of this device is as follows. The user places first, second, and third fingers in the openings 3 at the end of the frame 1, and then places his thumb in the thumb socket 43. This enables the user to firmly hold the device. Held in this fashion, when the user brings his hand back of his head in a natural position, regardless of whether the device is held in the left hand or in the right hand, the finger hold end 2 is uppermost and the comb guide 16 is in a lowermost position with the teeth 17 extending upwardly. Then, by bringing the device close to the head, the teeth 17 will engage the hair and movement of the thumb toward the fingers, which is a natural grasping movement, will act to swing the thumb section 43 forwardly and upwardly, causing the rockable cutter blade 39 to swing downwardly across the stationary blade 14 in hair-cutting relation. The blade 39 engages the cutterbar 14 at an angle, as best shown in Fig. 5, and the end of the blade 39 which first engages the cutterbar 14 is rounded, as indicated at 55 in Fig. 13. The relation between the end 55 of the blade 39 and the stationary cutterbar or blade 14 is controlled by shaft adjustment 28, 29, 30, described above. The other portions of the blade 39, as it moves across the fixed blade 14, are pressed against the latter by the spring 34 and associated parts, thereby assuring positive cutting or shearing action.

It is of course understood that the specific description of structure set forth above may be departed from without departing from the spirit of my invention as disclosed herein and as defined in the appended claims.

Having now described my invention, I claim:

1. A hair cutting device comprising, in general, a U-shaped frame having a central section and a pair of spaced apart apertured ends, each of the latter being slotted, a fixed cutterbar carried by said central section, a pivot shaft extending through said apertures, an oscillatable part comprising a curved blade holder having at its ends a pair of arms supporting the curved blade holder for oscillating back and forth across the fixed cutterbar, said arms being mounted on said shaft and said oscillatable part fixedly carrying a curved blade operable against said fixed cutterbar when said part is oscillated, and spring means acting between said frame and the end of said shaft that extends through said slotted end.

2. A hair cutting device comprising a frame having a finger hold section at one end and a yoke section at the other end, said finger hold section being provided with a plurality of finger-receiving holes, said yoke section lying in a plane at right angles to the plane of said finger hold section, a lever pivoted to said yoke section and including a thumb socket swingable toward and away from said finger hold section, and hair cutting means rotatably carried by said yoke section, between the side portions thereof and connected to be actuated by said lever.

3. A hair cutting device comprising a frame having a finger hold section at one end and a yoke section at the other end, said finger hold section being provided with a plurality of finger-receiving holes, said yoke section lying in a plane at right angles to the plane of said finger hold section, a stationary cutterbar carried by said yoke section, between the sides thereof, a blade yoke having side portions pivoted to the sides of said yoke for movement about an axis, in general, parallel to but spaced from said stationary cutterbar, a blade carried by the central portion of said blade yoke and shiftable across said stationary cutterbar in hair-cutting relation, and a thumb strap fixed to said blade yoke and shiftable toward said finger hold section for shifting said blade across the stationary cutterbar.

4. A hair cutting device comprising an elongated frame having means at one end to receive the fingers of one hand of the operator, a cutterbar carried at the other end of said frame transversely thereof, a U-shaped part disposed transversely of said frame at said other end and having side portions pivoted to the frame at points adjacent the ends of said cutterbar, a cutter blade carried by the central part of said U-shaped part and movable across said cutterbar, and a thumb piece fixed to said part and movable by the thumb of the operator toward said end of the frame for shifting said cutter blade across said bar.

5. A hair cutting device comprising an elongated frame having finger openings at one end and a forked section at the other end, the plane of said finger openings and the plane of said forked section lying at right angles, a U-shaped member disposed between the side portions of said forked section and having its sides fixed to the side portions of the forked section, a stationary cutterbar fixed to the central part of said U-shaped member, the sides of the latter being slotted, a rockable blade carrier comprising a U-shaped part having its sides apertured and including a central section swingable toward and away from the central part of said stationary U-shaped member, and a thumb strap fixed to the central section of said rockable blade carrier and movable, approximately, in the plane of said

finger openings at the other end of the frame and toward and away from said finger openings, a pivot shaft extending through the apertures in the sides of the rockable blade carrier and through the slots in the sides of the fixed U-shaped member, a cutter blade carried by the central section of said rockable carrier and shiftable across said stationary cutterbar when said blade carrier is rocked in one direction about said pivot shaft, and a spring encircling said shaft and having one end connected to the carrier and the other end connected to one side of said stationary U-shaped member so as to swing said blade carrier away from said cutterbar when pressure against said thumb strap is relaxed.

6. A hair cutting device comprising an elongated frame having means at one end to receive the fingers of one hand of the operator, a cutterbar carried at the other end of said frame transversely thereof, a U-shaped part disposed transversely of said frame at said other end and having side portions pivoted to the frame at points adjacent the ends of said cutterbar, a cutter blade oscillated by the central part of said U-shaped part and movable across said cutterbar, transversely of the plane of said cutterbar, a thumb piece fixed to said part and movable by the thumb of the operator toward said end of the frame for shifting said cutter blade across said bar, the frame having slots in the sides thereof, said U-shaped part having a shaft extending through the sides, and a spring for pressing the shaft toward the cutterbar.

7. A hair cutting device comprising an elongated frame having finger openings at one end and a forked section at the other end, the plane of said finger openings and the plane of said forked section lying at right angles, a U-shaped member disposed between said portions of said forked section and having its sides fixed to the side portions of the forked section, a stationary cutterbar fixed to the central part of said U-shaped member, the sides of the latter being slotted, a rockable blade carrier comprising a
